UNITED STATES PATENT OFFICE

138,055

DESIGN FOR A FLOWER URN OR SIMILAR ARTICLE

Nicolo V. Cristontello, Elmira, N. Y.

Application April 22, 1944, Serial No. 113,338

Term of patent 14 years

(Cl. D29—28)

To all whom it may concern:

Be it known that I, Nicolo V. Cristontello, a citizen of the United States, residing at Elmira, in the county of Chemung and State of New York, have invented a new, original, and ornamental Design for a Flower Urn or Similar Article, of which the following is a specification, reference being had to the accompanying drawing, forming part thereof.

I claim:

The ornamental design for a flower urn or similar article, as shown.

NICOLO V. CRISTONTELLO.
